CANOPIED MOTOR FUEL DISPENSER

Guilbert M. Hunt, Willowick, Ohio, assignor to Tokheim Corporation, Fort Wayne, Ind., a corporation of Indiana

Application March 13, 1958, Serial No. 50,013

Term of patent 14 years

(Cl. D52—2)

Figure 1 is a perspective view of the canopied motor fuel dispenser, illustrating one of the dial sides and the hose side, and showing my new design.

The opposite sides of the dispenser, not shown, are substantially the same as the corresponding sides which are shown.

I claim:

The ornamental design for a canopied motor fuel dispenser, as shown and described.
